Application April 3, 1944, Serial No. 529,356

7 Claims. (Cl. 200—5)

1

This invention relates to electrical switches for selective establishment of a plurality of alternative circuit connections and resides in a novel combination of circuit elements including a magnetic contactor switch and circuit selective elements, and also in a novel arrangement of electrical and mechanical elements by which alternative circuit selection may be established prior to admission of load current, and terminated subsequent to discontinuance of load current whereby power of moderate magnitude may be alternately controlled by a standard magnetic contactor of appropriate size for the power to be controlled and a simple and compact switching device of very small dimensions.

Heretofore where electrical power of moderate magnitude has been switched to admit or discontinue the same in a plurality of alternative circuits, as for the reversal or speed control of motors such as are employed for the actuation of machine tools, hoists and the like, it has been the common rule to provide selectively engageable contacts which in and of themselves act to admit and interrupt the load current. In so doing each pair of selective contacts or commutating members must be of sufficient size to withstand the arcing attendant upon interruption of the load current. For example if simple reversing of a motor is to be accomplished, either a commutating drum capable of withstanding the load current, or a pair of mechanically interlocked magnetic contactors both of sufficient size for the purpose must be employed. Where space is limited the cumbersome commutating drum often cannot be used, and if the pair of mechanically interlocked magnetic contactors are employed the expense of duplication of switching facilities half of which is idle at all times is involved. Where more than two alternative circuits must be provided for an increase in the problem in proportion to the number of alternative circuits required is encountered.

An object of this invention is to provide a small compact and comparatively inexpensive device which when employed in conjunction with a single standard magnetic contactor switch, will permit of the selection of a plurality of alternative circuits.

This invention is herein described by reference to the accompanying drawings forming a part

2

hereof in which there is set forth by way of illustration and not of limitation two specific forms in which the apparatus of this invention may be embodied. In the drawings:

- 5 Fig. 1 is a side sectional view of one form of the apparatus of this invention.
  - Fig. 2 is a top plan view with cover removed of the apparatus of Fig. 1.
  - Fig. 3 is an end view in elevation of the apparatus of Fig. 1.
  - 10 Fig. 4 is a sectional view in end elevation of the apparatus of Fig. 1 viewed through the plane 4—4 indicated in Fig. 1.
  - Fig. 5 is a sectional view in end elevation of the switch parts only of Fig. 1 viewed through the plane 5—5 indicated in Fig. 1.
  - 15 Fig. 6 is a sectional view in end elevation of the switch parts only of Fig. 1 viewed through the plane 6—6 indicated in Fig. 1.
  - 20 Fig. 7 is a fragmentary plan view in section of the switch parts appearing in Fig. 6, viewed through the plane 7—7 there indicated.
  - Fig. 8 is a sectional view in end elevation of the switch parts only of Fig. 1 viewed through the plane 8—8 there indicated.
  - 25 Fig. 9 is a sectional view in end elevation of the switch parts only of Fig. 1, viewed through the plane 9—9 there indicated.
  - Fig. 10 is a side view in elevation and in section of a somewhat simpler form of the apparatus of this invention.
  - 30 Fig. 11 is a top plan view of the apparatus of Fig. 10 shown with the cover removed, and with parts of the actuating handle and lock shown in section.
  - 35 Fig. 12 is an end view in elevation and in section of the apparatus of Fig. 10 viewed through the plane 12—12 there indicated.
  - Fig. 13 is an end view in elevation and in section of switch parts only of the apparatus of Fig. 10 viewed through the plane 13—13 there indicated.
  - 40 Fig. 14 is a circuit diagram illustrating one method of connecting the apparatus of Fig. 1 in circuit with a magnetic contactor, and
  - 45 Fig. 15 is a circuit diagram illustrating one method of connecting the apparatus of Fig. 10 in circuit with a magnetic contactor.
- The apparatus depicted in Figs. 1 to 9 inclusive is adapted for connection with a single

standard magnetic contactor as diagrammatically indicated in Fig. 14, to cause reversal of a three phase induction motor. In so doing the admission and interruption of load current is accomplished entirely by the magnetic contactor, with selector contacts which accomplish the reversing function being arranged to engage and disengage only when load current is excluded by open condition in the magnetic contactor. To this end the apparatus of Figs. 1 to 9 is provided with parts to be hereinafter referred to for energizing the magnetic contactor and with separate parts for preselection of alternative circuits.

Referring now particularly to Figs. 1 to 4 inclusive, the apparatus there shown is provided with a housing comprising a sheet metal base having a bottom 1 and upturned ends 2 and 3, and a separate complementary trough-shaped sheet metal cover 4 held in place by screws 5 and 6. Through a bushing 7 rigidly held in vertical end 3 by threaded engagement with nuts as shown, an axially and rotatably movable cam shaft 8 enters the housing referred to. An operating handle 9 is secured to the shaft 8 by set screw 10 as shown.

The inner end of shaft 8 is hexagonal in shape so as to permit a sleeve of insulating material 11 having a polygonal hole therein to be non-rotatably held thereon. To hold sleeve 11 rigidly against axial movement with respect to shaft 8, a C washer 12 held in a groove provided therefore in shaft 8 is placed at one end, and a slip-connection plate 13, washer 14 and screw 15 is provided at the opposite end.

Surrounding shaft 8 and sleeve 11 is an electrical contact mounting made up of interlocking segments of insulating material 16 and 17 clamped tightly together between endplates 18 and 19 by through bolts 20 and 21. The endplate 18 receives its support from bushing 7 and is held against rotation in the housing by a stand-off rivet 22 as shown. Bearing support for the inner end of shaft 8 is provided by engagement of the cylindrical surface of sleeve 11 with a circular opening provided therefor in endplate 19.

Shaft 8 as previously noted is mounted for and capable of axial movement and to provide for control of such movement and to cause said shaft to be self returning to a mid-rest position, a caged spring 23, is interposed between washers 24 and 25 through which shaft 8 is free to slide. Since washer 25 engages stationary bushing 7 and washer 24 engages segment 16, shaft 8 occupies a normal or rest position corresponding to the full line position of handle 9. Shaft 8 and handle 9, however, are capable of being moved axially to either of the positions indicated by dash dot lines when sufficient force is applied thereto to overcome the spring 23 which preferably is under a small initial compression.

Surrounding sleeve 11 and formed as a part thereof is a circumferential boss 26 the outer margin of which is arcuate in configuration as shown. Boss 26 is provided with two diametrically located gaps which are horizontally disposed when shaft 8 is in mid-angular position as illustrated by full lines in Fig. 3. The character and disposition of the gaps in boss 26 are clearly shown in Fig. 6.

Embraced and securely held by socketed engagement between segments 16 and 17 are movable contact mountings 27 and 28 carrying upwardly-extending, resilient, movable contact carriers 29 and 30, bearing movable contacts 31 and 32 at their upper ends. Also held between seg-

ments 16 and 17 are stationary contacts 33 and 34 disposed respectively to be engaged by movable contacts 31 and 32. Secured to carrier 29 is a follower point 35 adapted to be engaged by boss 26 to cause engagement of contacts 31 and 33 whenever shaft 8 is away from mid-angular position, and when in either mid or outer axial position. Secured to carrier 30 is a follower point 36 adapted to be engaged by boss 26 to cause engagement of contacts 32 and 34 whenever shaft 8 is away from mid-angular position and when in outer axial position.

While shaft 8 and handle 9 are free to move axially in any selected angular position, angular movement is subjected to limitation by reason of engagement of slip connection plate 13 with stopping means provided therefor. Plate 13 as appears clearly in Fig. 5 is of roughly semi-circular shape limited in total angular displacement by stop pins 39 and 40 and provided with a series of circumferentially spaced perforations adapted for sliding engagement with stationary stop pin 37 rigidly attached to endplate 19. As appears in Fig. 7 the length of the stop pin 37 is such that it precludes angular movement of shaft 8 except when in inner axial position only.

The parts thus far described constitute the parts for causing energization of the magnetic contactor and for recapitulation of the function of which this part of the apparatus is capable, it is noted that with handle 9 in mid-angular position as illustrated in Fig. 3 it may be moved to any of the three axial positions 9, 9A or 9B illustrated in Fig. 1. In any of these no displacement of contacts 31 and 32 occurs because of the gaps in boss 26. In either of the other two angular positions of handle 9 designated in Fig. 3 "FOR" (forward) and "REV" (reverse) neither contact 31 or 32 is displaced in extreme inner axial position 9A, but in mid-axial position 9, contact 31 is displaced to engage contact 33, and in extreme outer axial position 9B, both contacts 31 and 32 are displaced to engage contacts 33 and 34 respectively. The sequence of engagement starting from mid position angularly and normal position axially, is

	Control Position		Contacts Engaged
	Angular	Axial	
1	mid	9	None.
2	do	9A	Do.
3	FOR	9A	Do.
4	do	9	31-33.
5	do	9B	31-33, 32-34.
6	do	9	31-33.
7	do	9A	None.
8	mid	9A	Do.
9	do	9	Do.

The same sequence is followed with entirely comparable results in entering and leaving "REV" from mid-angular normal axial position.

Additionally it is feasible to pass directly from step 7 of the "FOR" sequence to step 3 of the "REV" sequence and vice versa to bring about engagement of contacts 31 and 32 with their corresponding stationary contacts without returning through steps 8 and 9 and reentering the sequence through steps 1 and 2. In all other respects the sequence of steps cannot be varied because of the engagement of pin 37 with slip connection plate 13 and motion limiting pins 39 and 40.

Rigidly attached to the contact mounting assembly comprising segments 16 and 17, is a switch body composed of segments 41, 42 and 43, having

a polygonal shaft 44 with a cylindrical end 45 joined in a bushing 46 held in an endplate 47 by a threaded engagement with a nut 48. Shaft 44 is held against endwise displacement by C rings received in slots in shaft 44 provided therefor, the same being disposed on opposite sides of bushing 46. Received on shaft 44 are insulating cam sleeves 49 and 50 which are spaced endwise by end collars 51 and 52. A screw 53 engaging the end of shaft 44 forces a cup washer 54 against the hub of a bifurcated arm 55 urging the same against the end collar 51 thus clamping the shaft-borne cam sleeves 49 and 50 in place.

The ends of bifurcated arm 55 terminate in parallel pins 56 and 57 rigidly united thereto which form a slip connection with perforations provided therefor in plate 13. Arm 55 is provided with a polygonal hole at the point of its engagement with shaft 44 and therefore must rotate therewith, and by reason of this and the engagement of pins 56 and 57 with plate 13, shaft 44 must at all times follow the angular movement of shaft 8 although it is at the same time incapable of axial movement and is independent of the axial movement of shaft 8.

A serrated indexing wheel 58 having a hexagonal hole engaging shaft 44 bears against collar 52 and is held in place thereby. Pivotal mounted upon plate 47 is a detent arm 59 bearing a detent roller 60 positioned to cooperatively engage the serrations in wheel 58 the same being urged into engagement by a spring 61 mounted as shown. While the wheel 58 is shown with serrations throughout its periphery, it will be understood that but three of these come into play, the remaining ones being provided only to facilitate revision of the structure for other function in the event that such be desirable. This detent mechanism provides the necessary restraint and "feel" by which the three selected angular positions can be achieved quickly and positively.

Held in place between segments 41 and 42 are movable contacts 62 and 63 and stationary contacts 64 and 65 and in like manner between segments 42 and 43 are movable contacts 66 and 67 and stationary contacts 68 and 69. These segmental switch parts including contacts, thus assembled, are held together by through bolts 10 and 11, and are constructed in accordance with my Patent No. 2,319,503, issued May 18, 1943, and therefore are not described in greater detail. Bolts 10 and 11 respectively threadingly engage spacer sleeves 72 and 73 and thus rigidly unite all of the switch contact mountings, including segments 16, 17, 41, 42 and 43. Plate 47 at its lower end is provided with a T slot positioned and conformed to engage the head of rivet 74, secured to the base 1 whereby the entire switch assembly is rigidly fastened within the housing but is readily removable as a unit simply by removal of the outer nut engaging bushing 7.

Cam 49 as appears more clearly in Fig. 8 is provided with a cam point 75 which comes into play to cause engagement of contacts 62 and 64 whenever handle 9 is in the "FOR" angular position and a cam point 76 which comes into play whenever handle 9 is in the "REV" angular position. Cam 50 as appears more clearly in Fig. 9 is provided with a cam point 78 which comes into play to cause engagement of contacts 67 and 69 whenever handle 9 is in the "FOR" angular position and a cam point 77 which comes into play to cause engagement of contacts 66 and 68 whenever handle 9 is in the "REV" angular position.

In Fig. 14 is illustrated the use of the appara-

tus above described for controlling a reversible 3 phase induction motor 79 having an overload cut out switch 80.

In this application a three wire pilot circuit is used providing for low voltage protection; also the provision that on occurrence of overload the control lever must be manually operated before motor is energized again. Also an important feature is obtained in this illustration, namely, with motor running in the normal forward or reverse position the power may be disconnected instantly by pushing the control handle inwardly.

For this purpose a single standard magnetic contactor switch designated generally by the numeral 91 is connected to join the line leads 81, 82 and 83 respectively with leads 84, 85 and 86. Switch 91 is provided with bridging contacts 87, 88 and 89 proportioned to interrupt load current without damage. Lead 86 is joined to contact 62 and by bridging conductor 92 to contact 63, lead 84 is joined with contact 66 and by bridging conductor 93 with contact 67. Lead 85 is joined permanently with one of the terminals of motor 79. Another terminal of motor 79 is joined by the lead 84 and bridging conductor 95 with contacts 64 and 68. The remaining terminal of motor 79 is joined by lead 96 and bridging conductor 97 with contacts 69 and 65, to complete the load carrying circuit elements.

In the control circuits line lead 81 is arranged for permanent connection with contact 34 by means of lead 98, while contact 33 is joined for access to lead 81 through lead 99 and magnetically controlled auxiliary contact 100. Movable contacts 31 and 32 are joined by a bridging conductor 101 and connected through lead 102, overload switch 30, and lead 103 with one end of magnet coil 90 the opposite end of which connects through lead 104 to line lead 82.

It will be observed by reference to the foregoing sequence table, that immediately on attainment of step 3 "FOR," contacts 62 and 64 engage and also contacts 67 and 69, but no load current passes because contactor switch 91 is still open. This condition still prevails in step 4 "FOR," since engagement of 31 and 33 occurs with 100 still open. However upon attainment of step 5, 32 and 34 engage supplying control current from lead 93 to 102, 30, and 103 to the magnet coil 90. Thereupon the switch 91 closes which includes the closure of 100.

The operator may now release the handle 9 and it will move of its own accord to and be mechanically self-retaining in step 6 and the circuit will be electrically self-retaining also so that motor 79 will continue to run in the forward direction until an overload causes 30 to open or until the operator presses handle 9 to move to step 7. Since step 5 cannot be achieved without first passing through step 3 and since step 8 cannot be achieved without first passing through step 7, contacts 62 to 69 inclusive can never be called upon to either make or break a load circuit. This is equally true in the "REV" sequence and also in the short cut between "FOR" and "REV."

The presetting of the selector contacts and the control of admission of load current by the magnetic contactor switch makes feasible the use of selector contacts of very much lighter and simpler character permitting the assembly of Figs. 1 and 2 to be constructed in extremely compact form considering the magnitude of load current passing therethrough.

The apparatus of this invention may be con-

structed in somewhat simpler form based upon the two wire system of control as appears in Figs. 10 to 13 and 15. In this case a similar housing made up of a base 104 with upstanding ends 105 and 106 and a cover not shown is provided. An axially shiftable rotatable shaft 107 enters the housing through a bushing 108 locked in place in end 106 by nuts as shown. Shaft 107 carries adjacent to the locked in place C washer 147, and rigidly associated therewith an indexing wheel 109 which cooperatively engages a grooved detent roller 110 mounted to slide axially on horizontal pin 111 carried upon pivoted detent arm 112. A spring 113 urges arm 112, pin 111 and roller 110 into engagement with wheel 109 at all times.

Inwardly adjacent to the wheel 109 and rigidly secured to shaft 107 is a cam sleeve 114 of insulating material having a boss 115 arcuately formed on its outwardly facing side. The boss 115 has a peripheral gap 116 as appears more clearly in Fig. 13. Boss 115 is disposed in a cell formed between insulating contact supporting segments 117 and 118 in position to engage the follower point 119 of a movable contact carrier 120 mounted therein. Carrier 120 is provided with a movable contact 121 disposed at its upper end in position to engage a stationary contact 122. The parts thus far described are those whose function it is to control the energization of a magnetic contactor load switch.

Beyond the sleeve 114 are two cam sleeves 122 and 123 disposed respectively in cells formed between insulating contact mounting segments 124 and 125, and 126 and 127. Sleeve 122 is provided with cam points 125 only one of which is shown, and sleeve 123 with cam points 126 only one of which is shown. The points 125 and 126 are disposed similarly to cam points 75, 76, 77, and 78, and are adapted to actuate contact pairs 127-128, 129-130, 131-132, and 133-134 in an entirely similar fashion.

A cylindrical spacer sleeve 135 at the end of shaft 107 passes through a circular end plate 136 which serves as a journal in which the same may freely move both axially and angularly. End plate 136 in conjunction with end plate 137 and through bolts 138 and 139 serve to bind the contact supporting segment assembly into a unitary whole.

Secured to the inner end of shaft 107 to turn and move axially therewith is a rotation-stop finger 140, carrying a short pin 141 which is disposed parallel with shaft 107. Pin 141 is adapted to selectively engage three perforations 142 formed in end plate 136 and when in engagement with any one of them to prevent the turning of shaft 107 but at the same time to permit free axial movement thereof.

Beyond the end of shaft 107 and held in place by spacer sleeves 143 and screws 144 is a spring seat 145, which serves as a means for retaining a spring 146 which bears upon the end of shaft 107 and constantly urges the same to its outer axial position determined by engagement of C washer 147 with the inner end of bushing 108.

A C washer 190 is provided on shaft 107 to limit inward motion of shaft.

By reason of the construction above described shaft 107 and associated parts can occupy two axial positions, i. e. an inner and an outer position and can occupy three angular positions, i. e. a mid-position, a "FOR" position and a "REV" position. Further it will be apparent that angular movement can only take place while shaft 107

75

is occupied in its inner axial position. Motion sequences mechanically imposed are therefore subject to the limitation that angular change in outer position can only take place with an intervening axial inward position.

This sequence limitation is availed of by so positioning follower point 119 with respect to boss 115 that contacts 120 and 121 are brought into engagement whenever shaft 107 is in its outward axial position except when gap 116 is in registry with follower point 119, which latter occurs only when shaft 107 is in its mid angular position. Furthermore cam points 125 and 126 are of sufficient axial extent so as to perform their function of causing engagement of the contacts corresponding thereto when shaft 107 is in either its inner or outer position.

Starting therefore with shaft 107 in its mid-angular and outer axial position, the following functions are available:

20 Knob 148 is non-rotatable in the position assumed at the start and it must first be forced inwardly to permit it to be turned. If turned to the right to the inward "FOR" position contacts 129-130 and 127-128 are engaged. If shaft 107 is then permitted to return to its outer axial position without rotation contacts 128-129 will become engaged in addition to those already named. Further movement from the latter position can only be achieved by again forcing knob 148 and shaft 107 inwardly and when this is done contacts 120-121 separate. Following this knob 148 can be turned either to mid position and released to disengage all contacts or to "REV" angular position to engage contacts 131-132 and 129-130 whereupon contacts 120-121 may be re-engaged by allowing axial return of shaft 107 to its outer axial position. Of course the sequence outlined may be reversed if desired, that is to say, "REV" positions may be entered instead of "FOR" positions and outer mid position can be reached from either without passing through the other.

Set forth in Fig. 15 is a circuit adapted to utilize the properties of the apparatus of Figs. 10 to 13. There is here shown a three phase induction motor 150 with its three terminals 191, 192, and 193. Motor terminal 191 is connected through line 194 to contact 132 and through jumper 195 to contact 128 of the control switch. Motor terminal 192 is connected through line 196 to contact 134 and through jumper 197 to contact 130 of the control switch.

Motor terminal 193 is connected through lead 198 to terminal 199 of magnetic contactor designated generally as 167. Terminal 200 of magnetic switch is connected through conductor 201 to movable contact 127 and through jumper 202 to movable contact 129. Terminal 203 of magnetic switch is connected through conductor 204 to movable contact 131 and through jumper 205 to movable contact 133. The electric power supply is connected to the magnetic switch through conductors 206, 207, 208 to terminals 209, 210 and 211 respectively. The magnetic coil 167 is connected at one end to terminal 210 and its other end is connected through conductor 212 to overload switch 164, thence through conductor 213 to movable contact 120 of the control switch. Contact 120 is arranged to engage stationary contact 121 and the latter is connected to conductor 214 to terminal 209 of the magnetic switch.

When the apparatus of Figs. 10 to 13 is actuated as above described by movement for example from mid outer position to inner "FOR" positions 75 contacts 133-134 and 127-128 engage prepara-

tory to admitting forward driving current to motor 150. No load current is admitted at this stage, however, since switch 157 is still open. As soon, however, as the control is permitted to assume the "FOR" outer position contacts 121—126 close energizing coil 167 and closing switch 157. The knob 148 can then be released and it will be self-retaining in this position and motor 150 will continue to run in the forward direction. The only movement of which the control is capable in this position is an inward motion and as soon as this is executed switch 157 is opened while 133—134 and 127—128 remain in engagement. Switching from forward to reverse and vice versa or entry of reverse directly from mid position will be readily understood to be likewise accomplished with power current admission or interruption controlled solely by switch 157. It is to be understood that the motor control circuit as described in connection with Figs. 10, 11, 12, 13 and 15 is of the so-called two wire control and provides only no voltage release.

Contained within knob 148 is a key controlled cylinder lock 169, having a transversely extending bolt 170 actuated by key 171. Bolt 170 is adapted to engage either of slots 172 or 173. When bolt 170 is in slot 173 as shown in Fig. 11 a slideable captive pin 174 precludes normal inward movement of knob 148 and thus effectively "locks" the switch in either of the "on" positions or in the "off" position. By lodging the bolt 170 in slot 172 pin 174 is no longer held in projected position and the switch is free to function in normal manner.

It is to be noted that the lock device contained within the manually operable handle functions on the basis of an axial displacement, namely within the handle is an element under the control of a key, which element is manually displaced and locked, and while in this position the switch cannot be turned to another position. As the control switch herein described is based upon an axial motion together with a rotary motion it is seen that the lock device is coordinated with the very motions of the control switch. It is understood that this lock device may be used with any control switch which is provided with an operating mechanism which is pushed in to be turned.

While there has been herein described the utilization of the apparatus of this invention to accomplish motor reversal it will be apparent to those skilled in the art that the apparatus of this invention will be equally useful in cases where alternative circuits are to be selected for other purposes.

I claim:

1. In a switch adapted to select a plurality of circuits the combination comprising, a shaft mounted for axial and rotative movement, means adapted to prevent rotative movement of said shaft except in a selected axial position, a plurality of circuit selecting contacts, means adapted to cause and maintain engagement of alternative groups of said circuit selecting contacts when said shaft is in selected rotative positions, a pair of control circuit contacts, and means adapted to cause engagement of the same when said shaft is in an axial position other than one in which it is capable of rotation.

2. In a switch adapted to select a plurality of circuits the combination comprising, a shaft mounted for axial and rotative movement, means adapted to prevent rotative movement of said shaft except in a selected axial position, a sec-

ond shaft mounted for rotative movement, means adapted to cause said second shaft to be rotated by said first shaft independent of axial movement thereof, a plurality of circuit selecting contacts adapted to be selectively engaged in alternative groups in response to selective rotative positions of said second shaft, means preventing rotative movement of both shafts except when said first named shaft is in a selected axial position, and control contacts adapted to be engaged upon axial movement of said first named shaft away from an axial position in which it is capable of rotation.

3. In a switch having an "off" position and adapted to select a plurality of circuits the combination comprising, a shaft mounted for axial and rotative movement, means adapted to preclude rotation of said shaft except in a selected axial position, a plurality of circuit selecting contacts, means adapted to cause and maintain engagement of alternative groups of said circuit selecting contacts when said shaft is in selected rotative positions, said shaft having a rotative position in which none of said circuit selecting contacts are engaged, control circuit completing means comprising a pair of contacts, and means adapted to cause engagement of said control circuit contacts when said shaft is in an axial position other than one in which it is capable of rotation and an angular position other than a position in which which none of said circuit selecting contacts are in engagement.

4. In a switch adapted to select a plurality of circuits the combination comprising, a shaft mounted for axial and rotative movement, means adapted to preclude rotative movement of said shaft except in a selected axial position, a plurality of circuit selecting contacts, means adapted to cause and maintain engagement of alternative groups of said circuit selecting contacts when said shaft is in selected rotative positions, a control circuit means including pair of contacts, means adapted to cause engagement of said control contacts when said shaft is in an axial position other than one in which it is capable of rotation, and locking means for locking said shaft in an axial position in which rotation is precluded.

5. In a switching apparatus the combination comprising a plurality of stationary contacts, a plurality of movable contacts arranged to selectively engage said stationary contacts, an operating member therefor adapted to cause selective engagement thereof capable of axial movement between a plurality of axial positions and capable of angular movement in some of said axial positions and prevented from angular movement in others of said axial positions, and locking means associated with said operating member adapted when locked to rigidly restrain said operating member in one of said axial positions in which rotary movement is prevented.

6. In a switching apparatus the combination comprising a plurality of stationary contacts, a plurality of movable contacts arranged to selectively engage said stationary contacts, an operating member therefor adapted to cause selective engagement thereof capable of axial movement between a plurality of axial positions and capable of angular movement when in some of said axial positions and prevented from angular movement in others of said axial positions, a lock mounted upon and in alignment with said operating member having a locked position in which said operating member is rigidly restrained against axial movement when said operating member is in an

axial position in which angular movement is prevented.

7. In a switch adapted to select a plurality of circuits the combination comprising a first group of contacts adapted to be engaged alternatively in sets, a separate set of control contacts, means movable first to cause engagement of some of said first group of contacts and thereafter movable while maintaining said engagement of said first group of contacts to cause engagement of said control contacts, and means preventing disengagement of said first group of contacts until after disengagement of said control contacts.

MANFRED L. GLOGAU.
